UNITED STATES PATENT OFFICE.

WILLIAM H. GERRARD, JR., OF YAZOO CITY, MISSISSIPPI.

ROCKER ATTACHMENT.

1,231,151.

Specification of Letters Patent. Patented June 26, 1917.

Application filed December 10, 1915. Serial No. 66,139.

To all whom it may concern:

Be it known that I, WILLIAM H. GERRARD, Jr., a citizen of the United States, residing at Yazoo City, in the county of Yazoo and 5 State of Mississippi, have invented certain new and useful Improvements in Rocker Attachments, of which the following is a specification.

My invention relates to chairs and more 10 particularly to a rocker attachment therefor.

The primary object of my invention resides in the provision of a novel rocker attachment embodying novel means for 15 removably clamping the attachment to the legs of a stationary chair to consequently provide a rocking chair, novel means being also provided for permitting of the adjustment of the rockers with respect to each other so 20 that they may be readily applied to stationary chairs of various widths.

Another object of my invention resides in the provision of novel connecting means for 25 association with both rockers and the legs of the chair, said connecting means being incidentally formed of two sections which are adjustable relative to each other so that the rockers may be readily connected in the proper position regardless of whether or not 30 the distance between the rear legs varies from the distance between the front legs, said means also permitting of the raising of the front legs or the rear legs to a sufficient extent to provide an efficient rocking chair.

A still further object of my invention resides in the provision of a device of the character described that is simple in construction, efficient in operation and one that can be manufactured and placed upon the 40 market at a minimum cost.

Other objects as well as the nature, characteristic features and scope of my invention will be more readily understood from the following description taken in connection with the accompanying drawings and 45 pointed out in the claims forming a part of this specification.

In the drawings:—

Figure 1 is a side elevational view of my 50 invention, the forward rocker and the forward leg being broken away to show the manner in which the device is associated with the rocker and leg on the inside, and to also illustrate the arrangement of the adjustable connecting bars.

Fig. 2 is a top plan view of my invention to illustrate the arrangement of the adjustable connecting bars, the chair not being shown.

Fig. 3 is an enlarged vertical sectional view of the means for connecting the rockers to the legs of the chair.

Fig. 4 is a front elevational view of the 65 serrated surface of one of the clamping screws.

Referring more particularly to the drawings in which similar reference numerals designate like and corresponding parts throughout the different views, 1 indicates the usual stationary chair having a back 2 connected thereto and rear and front legs 3 and 4 respectively, connected together by suitable cross bars 5. It is to be understood that this type of chair forms no essential part of my invention being merely illustrated and 70 described in order that a thorough understanding of the invention may be set forth. The improved rocker attachment generally designated 6 is adapted to be removably connected with the lower edges of the chair legs 75 3 and 4, when it is desired to convert a stationary chair into a rocking-chair. In the present instance, the attachment comprises two similarly constructed arcuate rockers 7 which are adjustably connected to each other 80 through the medium of adjustable connecting means consisting of the tubular bars 8, each having a reduced and solid end 9 extending through suitably spaced transverse 85 openings in one of the rockers. Washers 90 10 and 11 are provided on the end 9 of each member 8 and are arranged on opposite sides of the rocker and a securing element 12, such as a nut or the like, engage the extremity of the end 9 of said bar for remov- 95 ably maintaining the latter in a position laterally of the rocker as illustrated. Rods 13 similarly secured to the other rocker are adapted to telescopically engage the tubular 100 bars 8 of the companion rocker. These rods having the reduced end 14 which extends through suitably spaced transverse openings 105 in the said other rocker 7 and carry washers 15 and 16 which are disposed on opposite sides of the rocker, for purposes well understood, the fastening devices 17 finally securing the rods in position. To maintain the bars 8 and 13 in adjusted positions to consequently regulate the distance between the 110 rockers, there is provided a holding means,

preferably consisting of set screws 18 threaded in the tubular bars 8 to frictionally engage the rods 13.

The rockers 7 are removably connected to the legs 3 and 4, after the rockers have been adjusted relatively to each other, sufficiently for this purpose, by connecting means, each of which preferably consists of channel-shaped elements 19 and 20 adjustably connected together by a threaded stud 21 projecting from the channel elements 19 and engaging in a correspondingly threaded socket 22 projecting from the opposing surface of the channel-shaped element 20. One of the arms of the channel-shaped elements is provided with a threaded opening in which is adjustably mounted a clamping screw 23. Each of these clamping screws has a finger piece 24 on the outer end thereof, while the inner end of each has a disk 25 thereon, the inner surface of the latter being serrated as indicated by the numeral 26. The inner faces of the other arms of the channel elements are also serrated as at 27 to coöperate with the serrated faces 26 of the disks when the parts are in engagement with the legs of the chair, for facilitating the engagement thereof. These channel-shaped clamping elements are arranged in straddled relation respectively with the front and rear legs of the chair and with the rockers, the clamping screws being rotated so as to removably clamp the legs and rockers between the serrated surfaces 26 and 27, adjustment of these clamping elements being facilitated through the medium of the stud 21 and complementary socket. This is particularly true when the distance between the rear legs is less than the distance between the front legs.

Although I have shown and described the preferred embodiment of my invention, I desire it to be understood that I am not to be limited to the exact details shown, however, I desire that great stress be laid upon the arrangement of the channel-shaped clamping and connecting elements for removably and adjustably associating the rockers with the legs of the chair as well as the adjusting means for connecting the rockers to each other so that they may be readily applicable upon the legs of any stationary chair.

Copies of this patent may be obtained for five cents each, by addressing the "Commissioner of Patents, Washington, D. C."

From the above description taken in connection with the accompanying drawings, it can be easily seen that I have provided a device that is simple in construction, containing but a few simple parts that can be cheaply manufactured and assembled and when assembled can be sold at a minimum cost.

It will be understood that the above description and accompanying drawings comprehend only the general embodiment of my invention and that various minor changes in detail of construction, proportion and arrangement of the parts may be made within the scope of the appended claims and without sacrificing any of the advantages of my invention.

Having thus fully described my invention, what I claim as new and desire to secure by Letters Patent, is:—

1. A rocker attachment for chairs comprising a rocker, means for adjustably connecting the rocker to legs of the chair and comprising a pair of channeled clamping members, a threaded stud projecting from one of the channeled members, a corresponding socket projecting from the opposing face of the other channeled member for adjustably receiving said stud, and means for clamping legs of the chair and the rocker in the channels of said members to maintain the parts in relative coöperative relation.

2. A rocker attachment for chairs comprising, a pair of rockers, means for adjustably connecting the rockers to the legs of the chair, said means including channel-shaped clamping members, a threaded stud projecting from the under surface of one of the channel members, a corresponding socket projecting from the upper surface of the other channel member for adjustably receiving the stud, and set screws adjustably mounted in each of said channel members for removably clamping the legs of the chair and the rockers and consequently maintain the parts in operative relation.

In testimony whereof I affix my signature in presence of two witnesses.

WILLIAM H. GERRARD, JR.
